HENRY W. STRUSS, OF NEW YORK, N. Y.

SPRING CONSTRUCTION

Application filed January 28, 1929. Serial No. 335,719.

The present invention is concerned with spring construction primarily adapted for use in upholstering furniture, but capable of varied uses which will be herein apparent.

5 It is among the objects of the present invention to provide an upholstered construction which combines the qualities of durability with the improved qualities of comfort.

It is a further object of the present invention to provide an improved spring construction which avoids the foundation of interlocking webbing and crossed cords as previously utilized.

10 It is a further object of the present invention to provide a spring construction in which the cords and webbing usually utilized are replaced by skeleton frames of flexible metallic strips whereby durability and the prevention of bunching of the springs are 20 provided for.

15 In accordance with the present invention, I utilize two skeleton frames or platforms of flexible metallic strips, one to be nailed to the lower side of the chair seat frame and so constructed that the springs may be readily put in place and held there by clips, riveted or spot-welded to the strips, or by extruded portions of the strips. The upper or floating platform may then be laid on top of the set of springs, the outer springs being then fastened by turning over the ends of the strips and secured by rivets or the like, the inner series of springs being suitably secured to the strips by clips, as will be herein illustrated. The construction of the skeleton frame is such that while the springs are held firmly in place they are at liberty to freely work separately or jointly, thus providing for the ease of the crossed cord construction

25 while providing improved durability. If desired, the assembly may be completed, and after assembly, positioned within the frame by nailing or the like, as will be clearly apparent from the following.

Numerous other objects and features of the

present invention will be apparent from a consideration of the following specification taken in conjunction with the accompanying drawings, in which

Figure 1 is a top plan view of one form of 50 my present invention;

Fig. 2 is a sectional view taken on the line 2—2 of Fig. 1;

Figs. 3, 4, 5 and 6 are detail views showing means forming part of my invention for securing the spring to the flexible strips, and

Fig. 7 is a top plan view of the invention as applied to a different arrangement of spring members.

Referring more particularly to the drawings, the seat frame is illustrated as at 10 in Figs. 1, 2 and 7. It will be understood that the frame 10 may be a removable spring frame or may be a portion of the frame of the article with which the springs are adapted to be associated. Associated with the frame and preferably secured thereto by fastening means disclosed as at 11 in Fig. 2, a base skeleton frame 12 is provided formed of crossed and interlaced flexible metallic strips 13, which extend longitudinally and transversely across to the opposite sides of the frame 10. Mounted upon the skeleton frame 12, preferably at the juncture of the strips 13 thereof, there are provided the usual set 75 springs 14 which are here shown as of the hour-glass configuration but which obviously may be of any desired type. These springs are arranged in longitudinal series 14a, 14b and 14c. The springs of the series 14a, 14b 80 are disposed in transverse alinement. The springs of the series 14c are located medially of and to one side of the spring series 14a, 14b.

The springs in the longitudinal series 14a, 85 14b constitute a major spring bank while the springs in the series 14c constitute what might be known as a minor spring bank. The springs in the series 14a, 14b are in closer formation respecting each other than they 90

are in respect to the springs 14c. This arrangement fortifies the front edge of the article of furniture in which the spring construction is embodied. Such front edge requires 5 to be fortified or reinforced in order to withstand the tendency toward distortion and possible destruction caused by a person sitting on such front edge. For securing the springs 14 against movement with respect to 10 the base 12, any of the desired clips as shown in Figs. 3 to 6, inclusive, may be utilized, detail description of the structure and operation of which will be hereinafter found.

For joining the upper ends of the springs 15 14 and thus securing them in their proper relation but permitting them independent flexing movement, an independent skeleton frame 15 is provided, which includes the transversely and longitudinally extending 20 flexible metallic strips 16 and 17, respectively. Each of the longitudinal strips 17 terminates at the outer convolution of the end spring of its series, each spring of the series being secured at both sides to the strips 17 25 through the provision of one or more of the clips shown. The end transverse strips 16a are connected with the transversely aligned springs in the series 14a, 14b, while the intermediate strips 16b are not only connected 30 to the remaining transversely aligned springs but have extensions 16c which are connected with the longitudinal strip of the spring series 14c. The strips 16d of the last series 14c are the shortest of all of the strips, and 35 after being connected with the springs of said series extend to points of connection with the longitudinal strip 17 of the adjacent series 14b.

A distinction can be made between the 40 various strips. Those which are connected with the spring series 14a, 14b of the major spring bank are to be identified as a network of strips. This network is not independent because it includes the extensions 16c which 45 couple it with the other strips of the minor bank 14c. Nor are the strips of this bank independent because each of the strips 16d is coupled with the foregoing network. The arrangement is obviously such that a free 50 and independent upper skeleton platform is provided which by virtue of the flexible material utilized, permits independent flexing of each spring and yet retains the springs in their proper spaced relation to prevent 55 bunching and to provide the desired staple characteristics of the spring construction.

In that form of construction as illustrated in Figure 7, it will be seen that the transverse and longitudinal strips 16 and 17, each terminate at the outer edge of the last spring of 60 the series with which they are associated and which are joined at the juncture thereof with the oppositely extending strips.

For providing ready means for securing the strips in conjunction with the springs 14,

the clips shown in Figs. 3 to 6 are illustrated. In connection with Fig. 3, the strips as indicated at 18, are provided with a clip 19 riveted to the strip as at 20 and under which the last convolution of the spring, as indicated at 21, is secured. After positioning of the convolution 21 under the clip 19, it will be readily seen that permanent association may be accomplished by bending inwardly the terminal point of the clip 19. 70 75

In connection with Fig. 4, there is provided an improved means of securing the extremity of the strip 18 in conjunction with the convolution 21 of the spring. In this instance, the strip 18 is bent to surround the spring convolution and a rivet or similar fastening means 22 is provided extending through spaced apertures in the strip 18, and bent to be permanently secured, thus preventing the removal of the convolution 21 from the extremity of the spring. 80 85

In connection with Fig. 5, it will be seen that for jointly securing two or more of the convolutions of the spring in association with the strips 18, double clip members 23 are 90 provided, each end of which may be turned over to surround and embrace one of the convolutions 21, similar to the construction shown in Fig. 3.

In connection with Fig. 6, it will be seen that a novel fastening means may be provided by extruding a portion 24 from the strip 18, which portion may be subsequently bent to surround the convolution 21 of the spring for retaining the same in proper association with the strip. 95 100

From the foregoing it will be readily seen that the present invention provides a novel spring construction which is of simple construction and operation, and which is readily designed to meet the demands of economic manufacture. 105

The invention provides a spring construction which combines the rigidity and permanency of a rigid construction with the individual elasticity of fabric connections between the springs. The invention also provides novel means for securing spring elements in conjunction with the strips. 110

It will be understood that numerous 115 changes and modifications of the present invention may be resorted to without departing from the spirit or scope thereof as outlined in the present claim.

What is claimed is:

A spring construction comprising a fixed supporting base, a plurality of coil springs secured to the base in longitudinal series, the springs of two of the series being disposed in transverse alignment and the springs of another series being located medially of and to one side of said first mentioned springs, a floating top skeleton frame secured to the springs, comprising a plurality of longitudinal strips substantially coextensive with the 125 130

respective series, a plurality of transverse strips connecting the springs of the transversely alined series, some of said transverse strips being extended to connect with the longitudinal strip of the medially arranged series, and other transverse strips connecting the springs of the medially arranged series with the longitudinal strip of one of the longitudinal spring series.
